UNITED STATES PATENT OFFICE.

JOSEPH M. DENNING, OF CEDAR RAPIDS, IOWA, ASSIGNOR TO DENNING TRACTOR COMPANY, OF CEDAR RAPIDS, IOWA, A CORPORATION OF IOWA.

PROPELLING MECHANISM FOR TRACTORS.

1,279,671.

Specification of Letters Patent. Patented Sept. 24, 1918.

Application filed September 22, 1916. Serial No. 121,554.

To all whom it may concern:

Be it known that I, JOSEPH M. DENNING, a citizen of the United States, residing at Cedar Rapids, in the county of Linn and 5 State of Iowa, have invented certain new and useful Improvements in Propelling Mechanism for Tractors, of which the following is a specification.

This invention relates in general to improvements in tractors of the type shown and described in my application Serial No. 49099, filed in the United States Patent Office on or about September 4th, 1915, and one of the objects of the invention is to 15 prove and simplify the propelling mechanism thereof.

A further object is to provide improved mechanism of this character which will be durable and cheap in construction and effective and efficient in operation.

To the attainment of these ends and the accomplishment of other new and useful objects as will appear, the invention consists in the features of novelty in substantially 25 the construction, combination and arrangement of the several parts hereinafter more fully described and claimed and shown in the accompanying drawings illustrating the invention and in which

30 Figure 1 is a top plan view of a portion of a tractor with parts removed, and having propelling mechanism connected therewith, constructed in accordance with the principles of this invention.

35 Fig. 2 is a vertical longitudinal sectional view as taken on line 2—2, Fig. 1.

Referring more particularly to the drawings, the tractor wheels 11, 12 are respectively connected with the axles 13, 14, the 40 latter being arranged in alinement with their inner ends in close proximity to each other, and being journaled in suitable bearings upon the side members 15 of a supporting frame or structure.

45 Connected respectively with the axles 13, 14 are gears 16, 17, to rotate therewith, and disposed between the gears 16, 17 is a sleeve 18, which serves in the capacity of a spreader for holding the gears 16, 17 separated.

50 A casing 19 is provided for housing the gears 16, 17, and this casing is supported in any desired or suitable manner from the frame work of the structure. The sleeve 18 also serves to hold the outer extremities

of the hubs of the gears 16, 17 against the 55 side walls of the casing 19.

Inasmuch as the axles 13, 14 are divided, the casing 19 in which the axles have a bearing, must be strong enough to support the weight of the machine. In order to impart rigidity to this casing, it is preferably made arch-shaped in the center as at 20 and a reinforcing or strengthening rib 21 is provided on the outside of the casing.

Journaled in suitable bearings 22 upon 65 the frame 15 is a driven shaft 23, commonly known as a jack shaft, and connected to this shaft for rotation therewith are gears 24, 25, which respectively mesh with the gears 16, 17 on the axles 13, 14.

An intermediate gear 26 is also connected with the shaft 23 and this gear meshes with a gear 27 that is connected with a driving shaft 28, the latter being journaled in suitable bearings 29 upon the frame work of the 70 machine.

All of the gears 16, 17, 24, 25, 26 and 27 are arranged within and housed by the casing 19 in order to protect the gearing and to permit the gearing to run in grease or oil, 80 that may be placed within the casing 19.

Connected with the shaft 28 is a gear 30, which meshes with a gear 31 that is secured to a shaft 32 journaled in suitable bearings 33 upon the frame.

Connected with this shaft 32 are spaced friction disks 34, 35 and between the disks a friction element 36 operates and this element 36 is connected with a shaft 37 of a motor 38.

The machine is advanced or moved backwardly by means of shifting the disks 34, 35 with respect to the element 36. The shaft 32 is mounted for longitudinal shifting movement in its bearings 33 and may be 95 shifted in any desired or suitable manner, not shown, so as to cause either one or the other of the disks 34, 35 to be moved into or out of engagement with the element.

Obviously a bearing may be substituted 100 for the sleeve 18 in which the ends of the axles 13, 14 project and in that event, the bearing may be held in position by being fastened within the casing 19.

With this improved construction it will 105 be manifest that the parts are not only compactly arranged and the gears completely housed and protected, but the parts

are so constructed that they may be readily and quickly assembled, while at the same time is produced an efficient propelling mechanism.

5 Furthermore with this construction it is possible by the use of this improved differential or compensating gear, for one traction wheel to travel at a different rate of speed than the other traction wheel when 10 turning.

What is claimed as new is:—

1. Propelling mechanism for tractors and the like embodying traction wheels, separate and alined axles to which the wheels are 15 respectively connected, a gear connected with each of the axles, a driven shaft, gears connected with the shaft and meshing respectively with the first said gears, an intermediate gear connected with the driven 20 shaft, a driving shaft, a gear connected with the driving shaft and meshing with the said intermediate gear, a casing housing all of 25 said gears, said casing having an arch shaped portion and a strengthening rib adjacent said portion, and mechanism for rotating the driving gear.

2. Propelling mechanism for tractors and the like, embodying traction wheels, separate and alined axles to which the wheels 30 are respectively connected, a gear connected with each of the axles, a sleeve into which the adjacent ends of the axles project, said sleeve also serving as a spreader for the 35 gears, a driven shaft, gears connected with the driven shaft and respectively meshing with the first said gears, a driven gear connected with the shaft, a driving shaft, a gear connected with the driving shaft and mesh-

ing with the last recited gear, and means for rotating the driving shaft.

3. Propelling mechanism for tractors and the like, embodying traction wheels, separate and alined axles to which the wheels are respectively connected, a gear connected with each of the axles, a casing housing said 45 gears, the hub of each of the gears abutting one of the walls of the casing, a spreader disposed intermediate the gears for holding them laterally separated, a driving shaft, and a gear connection between the said driv- 50 ing shaft and each of the said axles.

4. Propelling mechanism for tractors and the like, embodying traction wheels, separate and alined axles to which the wheels are respectively connected, a gear connected with each of the axles, a casing housing said 55 gears, the hub of each of the gears abutting one of the walls of the casing, a spreader disposed intermediate the gears for holding them laterally separated, a driven shaft, gears connected with the driven shaft and respectively meshing with the first said 60 gears, an intermediate gear connected with the shaft, a driving shaft, a gear connected with the driving shaft and meshing with the said intermediate gear, a casing housing all of 65 said gears, and means exterior of the casing for rotating the driving shaft.

In testimony whereof I have signed my 70 name to this specification, in the presence of two subscribing witnesses, on this 11th day of September, A. D. 1916.

JOSEPH M. DENNING.
